UNITED STATES PATENT OFFICE

MIRIAM GROSS, OF MILWAUKEE, WISCONSIN, ASSIGNOR TO MIRIAM GROSS COMPANY, OF MILWAUKEE, WISCONSIN, A CORPORATION OF WISCONSIN

DESIGN FOR KNITTED FABRIC

Application filed February 28, 1931. Serial No. 38,881. Term of patent 7 years.

To all whom it may concern:

Be it known that I, MIRIAM GROSS, a citizen of the United States, residing at Milwaukee, in the county of Milwaukee and State of Wisconsin, have invented a new, original, and ornamental Design for Knitted Fabric, of which the following is a specification, reference being had to the accompanying drawing, forming part thereof.

The drawing is a plan view of a piece of knitted fabric showing my invention, the detailed illustration contained in the center oblong section constituting the unit of the design, the extension of which beyond the unit boundaries shows its relation with the adjacent units.

I claim:

The ornamental design for knitted fabric as shown and described.

MIRIAM GROSS.
